CLAIM

The ornamental design for a bulkhead lamp, as shown and described.

DESCRIPTION

A portion of the disclosure of this patent document contains material, which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a frontal view of a bulkhead lamp showing our new design.

FIG. 2 is a left view of a bulkhead lamp showing our new design.

FIG. 3 is a back view of a bulkhead lamp showing our new design.

FIG. 4 is a right view of a bulkhead lamp showing our new design.

FIG. 5 is a top view of a bulkhead lamp showing our new design.

FIG. 6 is a bottom view of a bulkhead lamp showing our new design; and,

FIG. 7 is a perspective view of a bulkhead lamp showing our new design.

The broken lines in FIGS. 1 to 7 are for illustrative purposes only and form no part of the claimed design.
